UNITED STATES PATENT OFFICE.

OSCAR M. LEICH, OF GENOA, ILLINOIS, ASSIGNOR TO LEICH ELECTRIC CO., OF GENOA, ILLINOIS.

VIBRATORY CONVERTER.

Application filed December 31, 1921. Serial No. 526,344.

My invention relates to vibratory converters, and more particularly to a device of this character which is adapted for charging a storage battery, and which is provided with means for preventing discharge of the storage battery through the converter.

It is a purpose of the invention to provide a vibratory converter or rectifier that is provided with an armature which carries contact members that are adapted to cooperate with a pair of fixed contacts arranged on opposite sides of the contact carrying member. The contacts carried by the armature, and the fixed contacts are so related that the armature will not contact with the pole pieces of the magnet, thus preventing freezing or sticking of the armature to the pole pieces.

It is a further purpose of the invention to provide means cooperating with the movable contact carrying member, which is adapted to hold said movable contact carrying member in such position, when no current from the main source of supply is passing through the coils, that the movable contacts are out of engagement with the fixed contacts, thus preventing discharge of a storage battery which is being charged through the rectifier.

It is more specifically a purpose of the invention to provide a member which is connected with an armature adapted to be attracted by the electromagnets of the converter that is adapted to enter a recess in the movable contact carrying member to prevent movement thereof when the armature is not attracted by the electromagnet, the member being so mounted that it will be overbalanced so as to cause the point thereof that engages with the movable contact carrying member to engage therewith, unless the armature is attracted by the electromagnets of the converter.

It is also a purpose of the invention to provide a bracket member upon which the lower ends of the coils are mounted, and upon which the locking member for the movable contact carrying member is pivoted which is made of non-magnetic material.

Other objects and advantages of the invention will appear, as the description of the accompanying drawings proceeds. However, I desire to have it distinctly understood that I do not intend to limit myself

to the exact details shown or described, but that I intend to include as part of my invention all such obvious changes and modifications of parts as would occur to a person skilled in this art, and as would fall within the scope of the claims.

In the drawings:

Fig. 1 is a front elevation of my improved vibratory converter;

Fig. 2 is a fragmentary front elevation of the lower portion of the converter shown in Fig. 1 with the movable contact carrying member locked in central position;

Fig. 3 is a side elevation of the device shown in Fig. 1, showing the locking member in locking position; and

Fig. 4 is a fragmentary detail view of the end of the shaft for the armature.

Referring in detail to the drawings, the improved vibratory converter comprises a pair of coils 5 which are provided with cores terminating in the threaded end portions 6, said end portions being provided with the nuts 7 and 8 for holding the member 9 of insulating material in place thereon, said member 9 having a U-shaped bracket member 10 mounted thereon in any suitable manner, said member 10 being provided with ears 11 and 12 for supporting the shaft 13, said shaft 13 passing through openings in said ears and being held in fixed position relative to said ears by means of the member 14 secured to the ear 11 by means of the screw 15 and having a hook-like portion at 16 engaging with a suitable opening in the end of the shaft 13 to hold the same from turning.

Mounted on the shaft 13 is the armature carrying member 17 which is provided with the U-shaped bends 18 and 19 in the ends thereof which are provided with openings through which the shaft 13 passes, and which form bearings for the shaft 13, so that the member 17 can turn thereon. Secured in any suitable manner on the member 17 is the armature 20, said armature cooperating with the threaded pole pieces 6 of the electromagnets, of which the coils 5 are a part, in a well known manner. The U-shaped member 18 is provided with a screw 21 for securing the conductor 22 thereto, said conductor extending through an opening in the upwardly extending ear 23 on the U-shaped member 10, as will be clear from Fig. 3. The member 17 is provided with a depending end

portion 24 upon which is adjustably mounted the movable contact carrying member 25, said member 25 being adjustable by means of the slot 26 in the forked end portion of the member 25 and the screws 27, which are mounted in the member 24. The member 25 is provided with ears 28 upon which the spring contact members 29 are mounted, said spring contact members 29 being secured by means of the screws 30 and being secured in such a manner that they will be stretched or substantially taut when put in position on the armature carrying member, thus acting as substantially taut spring strips. The members 29 are provided intermediate the ends thereof with contact points 31, which are adapted to cooperate with suitable adjustable stationary contacts 32, which are provided with knurled end portions 33 for adjusting the same in the end portions 34 of the L-shaped members 35 carrying the same. The members 35 are secured to a suitable supporting member 36 of insulating material in any desired manner as by means of the screws 63, and having wiring terminals 64. Said mounting of the members 35 on the member 36 insulates the same from each other. The members 32 are held in adjusted position by the lock nuts 37 as will be clear. Secured to the lower ends of the coils 5 is a supporting bracket member 38 which is made of non-magnetic material, and is provided with the upwardly extending portion 39 at the forward end thereof and with a downwardly extending portion 40 at the rear thereof. The member 38 is secured to the cores extending through the coils 5 by means of the screws 41, and has secured thereto on the underside thereof the U-shaped member 42, the depending portions 43 of which are provided with apertures which serve as bearings for the shaft 44 extending between the same, said shaft 44 having mounted thereon so as to turn therewith the armature 45, said armature being provided with ears 46 having apertures therein through which the shaft 44 extends. The armature 45 is provided with an ear 47 upon which is mounted the finger 48, said finger 48 comprising an outer layer of insulating material which is held in position by means of the screws 49. The finger 48 is adapted to cooperate with the arcuate notch or recess 50 in the lower end portion of the movable contact carrying member 25. The armature also has rearwardly extending arms 51 which extend over the screws 41, said screws 41 being magnetized when a current passes through the coils 5 so as to attract the armature 45 drawing the arms 51 toward the screws 41. Said arms 51 are provided with suitable projections or lugs 52 thereon of non-magnetic material adapted to engage the screws 41 so as to prevent freezing or sticking of the arms 51 thereto.

It will be seen that when a current of sufficient strength to attract the armature 45 goes through the coils 5, the member 48 will be in the position shown in Fig. 1, and the armature 20 will be free to vibrate, thus causing the movable contact members 31 to cooperate with the stationary contacts 32 in the usual manner to convert an alternating into a direct current. It will be noted, that when a fixed contact is engaged by a movable contact that the armature 20 will be out of contact with the members 6 thus preventing sticking of the armature to the magnet poles. The armature 45 is so over-balanced that the same assumes the position shown in Fig. 3, when there is insufficient current passing through the coils 5 to attract the armature 45. Then the member 48 will enter the notch or recess 50, as shown in Fig. 2, and the movable contact carrying member will be locked in a central position with the contacts 32 spaced from the contacts 31 at both sides thereof, as will be clear from Fig. 2. As the contacts are separated under these circumstances, there will be no chance for a current to pass through the device, except when the source of alternating current is connected with the device. If any failure occurs in the source of alternating current, then the finger 48 will assume the position shown in Figs. 2 and 3 and prevent vibration of the armature and movable contact carrying member carried thereby. The upwardly extending end portions 39 of the member 38 carry the member 36 of insulating material, as will be clear from Fig. 3, the same being held in position by any suitable means, such as the screws shown in Fig. 3. Secured to the member 38 is the magnet 53. The shaft 13 is made so as to be fixed in the supporting bracket 10, and the member 17 is made so as to turn on the shaft 13 so that the parts can be readily renewed if any wear takes place where the shaft 13 passes through the member 17, all that is necessary being to replace the member 17 to renew the bearings for the shaft 13.

Having thus described my invention what I desire to claim and secure by U. S. Letters Patent is:

1. A vibratory converter of the character described comprising an electromagnet energized from a source of current, a vibratory armature, contact members mounted to move with said armature, stationary contacts cooperating therewith, and a member positively holding said movable contact members spaced from said stationary contacts when said energizing current does not pass through said electromagnet, said member having no influence on said armature while the same is vibrating.
2. A vibratory converter of the character described comprising an electromagnet energized from a source of current, a vibratory

- armature, contact members mounted to move with said armature, stationary contacts cooperating therewith, and a member for holding said movable contact members spaced from said stationary contacts when said energizing current does not pass through said electromagnet and having no effect on said armature when said electromagnet is energized from said source.
- 5 3. A vibratory converter of the character described comprising a vibratory member, contacts mounted thereon, stationary contacts cooperating therewith, means for holding said movable contacts spaced from said stationary contacts and electro-magnetic means for maintaining said holding means out of holding position when said converter is operating.
- 10 4. A vibratory converter of the character described comprising a vibratory member, contacts carried thereby, stationary contacts cooperating therewith, and a member out of engagement with said vibratory member when said converter is operating and adapted to engage said vibratory member to hold said movable contacts spaced from said stationary contacts when said converter is inoperative.
- 15 5. A vibratory converter of the character described comprising an electromagnet, a vibratory armature cooperating therewith, a movable contact carrying member vibrating with said armature, stationary contacts cooperating therewith and means for holding said movable contacts spaced from said stationary contacts comprising an armature adapted to be attracted by said electromagnet to hold said means in inoperative position.
- 20 6. A vibratory converter of the character described comprising an electromagnet, a vibratory armature cooperating therewith, a movable contact carrying member vibrating with said armature, stationary contacts cooperating therewith and means for holding said movable contacts spaced from said stationary contacts comprising a pivotally mounted locking member having an armature adapted to be attracted by said electromagnet to hold said locking member in inoperative position.
- 25 7. A vibratory converter of the character described comprising an electro-magnet, a vibratory member operated thereby, contacts mounted thereon, stationary contacts cooperating therewith and mechanical means controlled by said electro-magnet for holding the contacts on said vibratory member spaced from said stationary contacts.
- 30 8. In a device of the character described, an electromagnet, a vibratory armature cooperating therewith, contacts mounted to move with said armature, and cooperating stationary contacts, a stationary shaft about which said armature turns, a supporting bracket for said shaft, and a member on said bracket engaging said shaft to hold said shaft against rotation.
- 35 9. A vibratory converter of the character described comprising an electromagnet, a vibratory armature cooperating therewith, a movable contact carrying member vibrating with said armature, stationary contacts cooperating therewith, a bracket member of non-magnetic material supporting said electromagnet at the lower end thereof, and locking means for said movable contact carrying member pivotally mounted on said bracket.
- 40 10. A vibratory converter of the character described comprising an electromagnet, a vibratory armature cooperating therewith, a movable contact carrying member provided with a recess vibrating with said armature, stationary contacts cooperating therewith, a bracket member of non-magnetic material supporting said electromagnet at the lower end thereof, and locking means for said movable contact carrying member pivotally mounted on said bracket, said means comprising a locking finger on one end thereof adapted to enter the recess in said movable contact carrying member to lock the same against movement.
- 45 11. A vibratory converter of the character described comprising an electromagnet, a vibratory armature cooperating therewith, a movable contact carrying member provided with a recess vibrating with said armature, stationary contacts cooperating therewith, a bracket member of non-magnetic material supporting said electromagnet at the lower end thereof, and locking means for said movable contact carrying member pivotally mounted on said bracket, said means comprising a locking finger on one end thereof adapted to enter the recess in said movable contact carrying member to lock the same against movement, and an armature on the other end thereof adapted to be attracted by said electromagnet.
- 50 12. A vibratory converter of the character described comprising an electromagnet, a vibratory armature cooperating therewith, a movable contact carrying member provided with a recess vibrating with said armature, stationary contacts cooperating therewith, a bracket member of non-magnetic material supporting said electromagnet at the lower end thereof, and locking means for said movable contact carrying member pivotally mounted on said bracket, said means comprising a locking finger on one end thereof adapted to enter the recess in said movable contact carrying member to lock the same against movement, and an armature on the other end thereof adapted to be attracted by said electromagnet.
- 55 13. A vibratory converter of the character described comprising an electromagnet, a vibratory armature cooperating therewith, a movable contact carrying member provided with a recess vibrating with said armature, stationary contacts cooperating therewith, a bracket member of non-magnetic material supporting said electromagnet at the lower end thereof, and locking means for said movable contact carrying member pivotally mounted on said bracket, said means comprising a locking finger on one end thereof adapted to enter the recess in said movable contact carrying member to lock the same against movement, and an armature on the other end thereof adapted to be attracted by said electromagnet, said member being overbalanced so as to cause said locking finger to enter said recess due to the action of gravity.

45
13. A vibratory converter of the character described comprising an electromagnet energized from a source of current, a vibratory armature, a contact member mounted to move with said armature, a stationary contact cooperating therewith, and a magnetically controlled member for positively holding said movable contact member spaced from said stationary contact when said energizing current does not pass through said electromagnet.

14. A vibratory converter of the character described comprising an electromagnet ener-

gized from a source of current, a vibratory armature, a contact member mounted to move with said armature, a stationary contact cooperating therewith, and mechanical means controlled by said magnet movable into position to hold said movable contact member spaced from said stationary contact when said energizing current does not pass through said electromagnet.

In witness whereof, I hereunto subscribe my name this 30th day of November A. D., 1921.

OSCAR M. LEICH.
